UNITED STATES PATENT OFFICE.

BERNARD LIBERMAN, OF PHILADELPHIA, PENNSYLVANIA.

CIGAR BUNCHING.

Application filed November 24, 1920. Serial No. 426,184.

To all whom it may concern:

Be it known that I, BERNARD LIBERMAN, a citizen of the United States, residing at Philadelphia, in the county of Philadelphia, State of Pennsylvania, have invented a new and useful Method and Means for Cigar Bunching, of which the following is a specification.

The invention relates to improvements in method and means for cigar bunching.

Among the objects of the invention are the improved method and means for forming and delivering into the groove or pocket of the rolling bed, exact and measured charges of tobacco, comprising the filler; for preventing the escape of filler at the ends of the bunch when delivered to the groove; for keeping the filler in place and the binder smooth and unimpaired during the rolling operation; for adjusting the dimensions of the filler delivered to the groove of the rolling bed.

The invention comprises method and means for insuring a proper and even supply of scrap tobacco to the measuring and delivering device, for detecting foreign substances in the filler as the same moves toward said measuring and delivering device, for removing said foreign substances before the charge is delivered, for insuring a proper movement of the filler to the measuring means, and a proper introduction and settling of the filler into said measuring pocket.

Referring to the drawings, which illustrate, merely by way of example, suitable means for effecting my invention:

Fig. 1 is a side elevation of a cigar bunching machine embodying my invention.

Figs. 1^a, 1^b, 1^c and 1^d are fragmentary sectional views showing the conductor and plunger in different positions.

Fig. 2 is a front elevation of same.

Fig. 3 is a vertical section on line 3—3 of Fig. 2, on an enlarged scale.

Fig. 3^a is a fragmentary section showing element 20 in the discharging position.

Fig. 4 is a horizontal section on line 4—4 of Fig. 2.

Fig. 5 is a detail in perspective of the rotating device above the measuring device.

Fig. 6 is a view in perspective of the funnel and conductor for delivering to the groove in the rolling bed.

Similar numerals refer to similar parts throughout the several views.

The hopper 10 comprises the base portion 11, and the upwardly extending frame comprising the diverging arms or corner sections 12, and the top horizontal extensions 50 or braces 13. The sections 12 are in the form of angles, in cross section, adapted to form channels or ways for receiving the panels 14 of glass or other transparent material. The panels 14 are obviously tapered 65 downwardly to correspond to the spaces between said corner sections 12, and are removably fitted in said angle frames, and each may be individually or independently removed or partially removed from its normal position, to permit access to the hopper contents, in order to remove a foreign body which may be discovered in said contents and so as to cause a minimum disturbance of the balance of the contents. 75

The hopper 10 is provided with suitable stirrers such as the bars or fingers 15 mounted or secured in the rotating shafts 16. Lower down near the discharge end of the hopper, and just above the pocket of the 80 measuring device is the rotating shaft 17; to this shaft are secured the parallel arms or rods 18, by means of the connecting arms 19. The rods 18 are parallel to each other and to the axis of rotation or oscillation of the measuring and charging device 20. This shaft 17 is also provided with the radiating arms or fingers 21; the extreme outer ends of which project beyond the peripheral path of travel of the parallel rods 18. 85

The lower end of the hopper is provided with the arc shaped flanges 22, 22 forming a seat for the upper side of the measuring and charging element. This element comprises a cylindrical body 20 having a longitudinally 90 extending recess or pocket 24. This body 20 is mounted on a shaft 23 journaled in the supporting frame 25, which also supports the hopper 10. To this shaft 23 is secured the crank 26 which is connected by the rod 27 to the lever 28 pivoted at 29 to the frame 25 near the bottom thereof. Lever 28 is provided with the roller 30 cooperating with the groove or channel on the rotating cam 31. This cam 31 is mounted on the main driving shaft 32, and, in its rotation, causes the reciprocation of lever 28, connecting rod 27 and the oscillation of the cylindrical body 20 from the position shown in Fig. 3, in which it receives the charge from hopper 10, to the 105 position in which it discharges to chute 33, and back again. It will be noted that the 110

channel of cam 31, is so formed as to give a reasonably prompt movement of the body 20 from the receiving position to the discharging position and back again, but that a considerable portion of the channel, as at 34, is concentric with the axes of the cam, so as to cause a dwell of the body 20, while in the receiving position, to give time for the material forming the filler to work into the pocket or recess 24. It will also be noted that the sides of this channel 34 are slightly roughened or undulating to cause a continual slight shaking or agitation of body 20. This action is for the purpose of cooperating, while in the receiving position, with the other instrumentalities in filling the pocket, in that the shaking of the body 20, facilitates a settling of the tobacco more effectually in the pocket, and while in the discharging position, this shaking action, facilitates in emptying the pocket into the chute, in that the filler is more readily dislodged from the pocket by said shaking or agitation.

25 The member or body 20 is shown with a knife 35 lining one side of the pocket; this knife being adapted to cooperate with a knife 35', connected with the hopper, to sever any portions of scrap which may project above the margin of the pocket, as said margin passes under the edge of the hopper wall. This feature is made the subject of a copending application.

30 The following feature however is claimed 35 herein—

A portion of the hopper adjacent one side of the body 20, and approximately in line of travel of the pocket, is cut away to form an opening 36 corresponding substantially in 40 length to the length of the pocket 24. This opening 36 is normally covered and closed by the knife 35', and by the reinforcing plate or member 37 provided with one of the arc-shaped flanges 22. The knife 35' and member 37 are removably connected to the body of hopper 10, being removable for the purpose of gaining access to the hopper near the bottom thereof, and to the recess or pocket 24 in order to remove foreign bodies from 45 the tobacco therein, and is especially important for permitting the removal of hard bodies that may become lodged between the cooperating knives. Suitable securing means such as the screws 38, or any suitable 50 form of catches may be used for such disengageably securing to the hopper, the elements 35' and 37, normally form the closure of opening 36.

55 As above stated the element 20 discharges or delivers measured charges of filler or scrap tobacco to the chute or trough 33. This chute in turn delivers to the funnel 39 and delivering conductor or channel 40, which in turn delivers or discharges to the 60 pocket 41, formed in the rolling bed 42. It

being understood, of course, that the binder 47 is first placed on the usual bunching apron 48, and both are depressed into the said pocket 41 to receive the charge of filler. The lower end of conductor 40 is forced down into the pocket 41 before the discharge of the filler from said conductor. The control of the discharge of filler through the conductor or channel 40 to the bunching pocket 41, is as follows: The channel member 40, is shown in the elevated position in Figs. 1 and 1^a. The usual plunger 49, supported on the rod 50, is also in the elevated position. This plunger serves to prevent the filler from passing from element 39 to element 40 as shown in Fig. 1^a. When the element 40 descends to the pocket 41, it precedes the descent of plunger 49, so that communication is established between 39 and 40 to permit the discharge of filler to pocket 41 as shown in Fig. 1^b. The plunger 49 then descends to press the filler in the pocket 41, as in Fig. 1^c. In the reverse movement, element 40 precedes plunger 49, as in Fig. 1^d, which insures complete discharge of the 70 75 80 85 90 95 100 105 110 115 120 125 130 filler from 40.

The conductor or channel element 40 has its greater horizontal dimension corresponding substantially with the length of the bunch to be formed. It is provided with the end projections or wings 43. That is the walls of lesser horizontal dimensions extend below the margin of the walls of greater horizontal dimension, as shown in Fig. 6. 100 These wings or projections 43 are of such dimension and shape as to fit neatly in the pocket 41, near the two outer ends thereof, and serve to prevent the displacement of the tobacco filler, delivered to said channel; especially during its compression by the plunger 49. It will also be noted that the conductor 40 is made in two parts, held together in slidable engagement by any suitable means such as the adjustably supported 105 funnel actuating and supporting rods 45, so that the two sections, forming the conductor 40, may be telescoped or drawn apart, as desired, to form a conductor of required cross-sectional dimensions.

The operation.

As will be noted the hopper 10 comprises the base or metallic portion 11 and the upper structure or frame 12 having the transparent panels 14. The tobacco, for example scrap tobacco, forming the filler is supplied to the hopper, and it is important that this supply should be kept above the level of the lower hopper section 11 and so that said supply can always be observed through the transparent panels. It is also important that the level of the supply should be kept well above the top of the base portion 11, in order to secure a proper distribution and mingling of the coarser with the finer particles of to-

bacco, such as scrap, as the same moves toward the charging pocket 24 of member 20. As cooperating in maintaining an even and proper commingling of the particles of tobacco while in the hopper, the stirrers 15 mounted on the shafts 16 are kept rotating in the directions indicated by the arrows, see Fig. 3, so that there is a constant movement of the tobacco particles in the region of travel of the stirring fingers 15 within the hopper downwardly toward the middle part and upwardly adjacent the walls thereof. Beneath the plane of operation of the stirring fingers 15, is mounted the rotating shaft 17, parallel with the axis of member 20, and just above the pocket 24. Upon this shaft 17 are mounted the two parallel rods or bars 18. These bars are parallel with the axis of the shaft 17 and also parallel with the axis of the charging member 20, and as the shaft 17 rotates, these bars or rods 18 not only serve to agitate the tobacco lying in the path of travel thereof, but also serve to feed and press the tobacco or filler into the charging pocket 24. In order to prevent these bars from packing the tobacco against the adjacent walls of the hopper the stirring fingers 21 are provided, also mounted on shaft 17, and extending beyond the peripheral path of travel of the bars or rods 18, so as to break up any tendency to packing of material within the influence of said bars or rods 18 and also to cooperate with the general stirring and agitation of said tobacco filler. The rotation of the shafts 16 and 17 is effected in any suitable way, such for example, as a train of gears driven from the main driving shaft of the machine. As the tobacco or filler settles in the hopper, fresh tobacco is supplied thereto, and the required level can readily be watched through the transparent panels 14. In case some foreign substance such as a nail or stone, or bit of wood becomes mixed with the tobacco filler in the hopper this may usually be detected through one or the other of the glass panels 14, and that panel, which is nearest to said foreign substance, may be lifted sufficiently to permit the removal of said foreign substance with the minimum disturbance of the contents of the hopper.

In case a foreign substance escapes detection and works its way to the bottom of the hopper, such substance or body will usually be caught upon the rotation of the charging member 20 between the cooperating knives 35 and 35' when the same come together. In such case the rotation of member 20, due to a slipping belt or clutch, or other provision made for such emergency, will be stopped and the stationary knife, which is removably secured to the side of the hopper and serves as a closure of the opening 36, is temporarily removed for the purpose of withdrawing such foreign substance, where-

upon the said knife 35' is returned to its place, and the operation of the machine proceeds.

During the movement of the tobacco filler from the hopper 10, 11, into the charging pocket 24, the member 20, due to the roughened surfaces of the channel 34 of cam 31 as above described, is sharply shaken or agitated, to facilitate the settling of the material from the hopper into the pocket 24. We thus have in cooperation with the agitation or shaking of body or member 20, the stirring and agitation of the filler in the upper part of the hopper to maintain an even and uniform consistency of the filler, and a thorough stirring of the material or filler in the lower end of the hopper, cooperating with means for gently forcing the material into the pocket 24. In a similar way, while the pocket 24 is in the position discharging to the chute 33, the agitation or shaking of body 20 greatly facilitates the discharge of filler from the pocket.

It will also be noted that in the rotating movement of member 20 the cutting edge of knife 35 moves with a shearing action across the cutting edge of knife 35' to sever any projecting portions of the filler above the top margins of pocket 24 as said pocket passes under the arc-shaped flange formation of plate 22. This means is made the subject of a co-pending application, and is therefore not claimed herein, but the use of the stationary knife-blade 35' as a removable closure for the opening 36 at the base of the hopper, is claimed herein.

It will be noted that as the member 20 rotates from the receiving position shown in Fig. 3, to the position indicated in Fig. 3^a, the pocket discharges to the chute 33, which, in turn discharges to the funnel 39 and conducting element 40. In order that the filler may be discharged to the bunching pocket 41 in approximately the proper dimension for the cigar to be made, means are provided for adjusting the cross-sectional dimensions of the funnel 39 and conductor 40. This consists in forming said funnel and conductor in sections by a vertical line of separation, so that one section is adapted to telescope within the other when the same are moved in horizontal planes. These sections of the funnel and conductor are connected to the side members 44, which in turn are slidably mounted on the horizontal rods 45, so that said funnel and conductor elements may be moved to and away from each other as desired. The said elements are locked, in the required position of adjustment, by the set screws 46.

When the conducting channel or formation 40 is lowered so that the ends 43 extend to the bottom of pocket 41, as in Fig. 1^b, the filler is discharged to said pocket, and the plunger 49 then descends to compress the

filler therein between the ends 41 of formation 40. This not only serves to retain the filler undisturbed in the pocket during the withdrawal of the ends 41, but, since the 5 filler is composed of moist or damp tobacco, the compression thereof by the plunger, within the pocket and between the projecting ends 41, serves to give the body of filler a set or coherence which is maintained until 10 the same is enclosed by the binder.

What I claim is:—

1. In a cigar bunching device, the combination of a measuring and charging element having a suitably dimensioned receiving 15 space, means for agitating a supply of filler in proximity to said receiving space, and rotating means for simultaneously pressing filler into said receiving space.

2. In a cigar bunching device, the combination of a measuring and charging element having a suitably dimensioned receiving space, means for supplying filler to said receiving space and means for agitating said element, during the charging thereof, to facilitate 20 the settling of the filler therein.

3. In a cigar bunching device, the combination of a measuring and charging element, having a suitably dimensioned receiving space, means for supplying filler to said receiving space, means for moving the charging element from receiving to discharging position and vice versa, and means for agitating said charging element while in the discharging position.

35 4. In a cigar bunching machine, the combination of a bunching apron, means operating upon the apron to form a bunching pocket and to close the ends of said pocket, means for delivering measured charges of 40 filler to said pocket and means for pressing the entire upper surface of the charge into a horizontal plan below the margin of the pocket.

45 5. In a cigar bunching machine, the combination of a bunching apron, means operating upon the apron to form a bunching pocket and to close the ends of said pocket, means for delivering measured charges of 50 filler to said pocket and means for pressing the entire upper surface of the charge into a horizontal plan below the margin of the pocket during the withdrawal of said delivering means.

55 6. In a cigar bunching machine, the combination of a bunching apron and means forming a bunching pocket therein, means forming a channel for directing measured charges of filler to said pocket provided with end projections for closing the ends of 60 the pocket during delivery of filler thereto, and a plunger operating to compress the filler in the pocket, while the ends thereof are closed.

65 7. In a cigar bunching machine, the combination of a bunching apron, means operat-

ing upon the apron to form a bunching pocket and to close the ends of said pocket, means for delivering measured charges of 70 filler to said pocket and means for pressing the entire upper surface of the charge into a horizontal plan below the margin of the pocket until after the withdrawal of said delivering means.

8. In a cigar bunching machine, the combination of a bunching apron and means forming a bunching pocket therein, means for delivering measured charges of filler to said pocket, including a reciprocating channel structure having projecting formations integral therewith for closing the ends of 75 the pockets during said delivery, and a reciprocating plunger, operating in said channel structure, to compress the charge within the pocket during the withdrawal from the pocket of said projecting formations. 80

9. In a cigar bunching device, the combination of a hopper for scrap tobacco, means for receiving therefrom measured charges to form a filler, the said hopper being provided with a port and a closure for said port adjacent the point of discharge to the measuring device. 90

10. In a cigar bunching machine the combination of a measuring and charging element comprising an oscillatory member having a receiving pocket of required dimensions, a hopper delivering thereto, a rotating element having extensions parallel with the axis of the oscillatory member and adapted to pass across the mouth of the pocket, said rotating member also provided with projecting fingers moving in planes at right angles with said axis. 100

11. In a cigar bunching machine the combination of a measuring and charging element comprising an oscillatory member having a receiving pocket of required dimension, a hopper delivering thereto, a rotating element having extensions parallel with the axis of the oscillatory member and adapted 105 to pass across the mouth of the pocket, said rotating member also provided with projecting fingers moving in planes at right angles with the said axis and having ends extending beyond the peripheral path of said parallel extensions. 110

12. In a cigar bunching machine the combination of a measuring and charging element comprising an oscillatory member having a receiving pocket of required dimensions, means for rocking the oscillatory member with a dwell between rocking movements, and means acting during said dwell for agitating the said oscillatory member to facilitate the settling of the charge therein. 115 120

13. In a cigar bunching machine the combination of a measuring and charging element comprising an oscillatory member having a receiving pocket of required dimensions, means for conveying the charge de- 125 130

livered by the measuring element to the groove of the rolling bed, said means including a conductor provided with horizontally telescoping side walls and having the margins of its end walls projecting beyond the margins of its side walls, said projecting portions having marginal contours corresponding to the cross-sectional contour of the groove to form stops near the ends of 10 said groove.

14. In a cigar bunching machine the combination of a measuring and charging element comprising an oscillatory member having a receiving pocket of required dimensions, a hopper delivering thereto, provided with inclined corner extensions forming ways, and panels of transparent material removably seated in said ways.

15. In a cigar bunching machine, the combination of a measuring and charging element comprising an oscillatory member having a receiving pocket of required dimensions, and a hopper delivering thereto, said hopper comprising a construction providing 20 channels, and glass panels slidably positioned in said channels and each independently removable therefrom.

16. In a cigar bunching machine the combination of a measuring and charging element comprising an oscillatory member having a receiving pocket of required dimensions, a hopper delivering thereto, provided with a port in the wall adjacent the point of delivery of the hopper to said receiving pocket and a removable closure for said 30 port.

17. In a cigar bunching machine, the combination of a measuring and charging element comprising an oscillatory member having a receiving pocket of required dimensions, a hopper delivering thereto, means forming a knife edge as one margin of said pocket, the hopper being provided with a port adjacent the oscillatory member, and a removable closure for said port provided 40 with a knife for cooperating with the knife edge margin of the pocket.

18. In a cigar bunching machine, the combination of a measuring and charging element and a hopper delivering thereto, said 50 hopper provided with corner extensions flaring upwardly and forming ways for side walls removably seated therein.

BERNARD LIBERMAN.
